(57) **CLAIM**

The ornamental design for abutment for dental implant, as shown and described.

DESCRIPTION

1. Abutment for dental implant

1.1 : Perspective

1.2 : Front

1.3 : Back

1.4 : Left

1.5 : Right

1.6 : Top

1.7 : Bottom

The present design relates to an abutment for dental implant, wherein the broken line indicate the unclaimed portion of the article that do not form part of the claimed design and the dash-dot broken lines define the boundary of the claimed design and form no part thereof.
